[57] CLAIM

The ornamental design for a structural member, as shown
and described.

DESCRIPTION

FIG. 1 is a perspective view of a structural member, showing
my new design.

FIG. 2 is a side view thereof it is noted that the opposite side
is identical to the illustrated side.

FIG. 3 is a top view thereof.

FIG. 4 is a end view thereof it is noted that the opposite end
is identical to the illustrated end; and,

FIG. 5 is a bottom view thereof.

The structural member is broken away to denote indeterminate
length.
